UNITED STATES PATENT OFFICE.

WILLIAM C. HOBART AND FREDERICK A. NICHOLSON, OF TACOMA, WASHINGTON.

STICKER FOR DOOR STOCK.

Application filed January 5, 1925. Serial No. 569.

To all whom it may concern:

Be it known that we, WILLIAM C. HOBART and FREDERICK A. NICHOLSON, citizens of the United States, and residents of Tacoma, 5 in the county of Pierce, State of Washington, have invented certain new and useful Improvements in Stickers for Door Stock, of which the following is a specification.

This invention relates to woodworking 10 machinery and especially to that class known as "door stickers". The object of such a machine is to form the edges of the stock to the desired molded or straight shape for the stiles and rails used to make the frames 15 between which the thinner panels are secured to form doors. The object of this invention is to provide a machine which is capable of being speeded up to run several times faster than the usual rate for machines 20 of this character; and a further object is to provide such a machine in which stock which is slightly bent edgewise may be run and used in the manufacture of doors. Another object is to provide a machine which may 25 be quickly and easily adjusted and which is adapted to operate on stock which is made of a plurality of thicknesses of wood, glued together, to form the desired thickness for the door stiles or rails.

30 We attain these and other objects by the devices, mechanisms and arrangements illustrated in the accompanying drawings, in which—

Fig. 1 is a front elevation of the complete 35 machine;

Fig. 2 is a central vertical cross-section thereof, viewed from the left end of the machine and showing, however, the motors and cutter heads in dotted lines in order to 40 reveal the motor supporting and adjusting means;

Fig. 3 is a diagrammatic view of the gearing for driving the feed rollers, as viewed from the rear;

Fig. 4 is a vertical section of a part of the frame showing the main set of gears for driving the feed rollers;

Fig. 5 is a plan of a part of the machine showing the means for guiding the stock being worked on as it is fed through the machine; and

Fig. 6 is a section of a portion of the feed roller pressing and controlling means.

Similar numerals of reference refer to 55 similar parts throughout the several views.

The standard form of sticker is not adapted 60 for high speed work for several reasons and does not work so fast that it cannot be tended by one man at each end feeding stock or removing the finished material. If, however, 65 the speed of the machine is to be further increased it is necessary that it shall work faster than is practical for any man to feed, in other words it must be automatically fed and dispose of the finished stiles 70 or rails automatically. The first requirement, therefore, of a high speed machine is that the stock need not be handled in being fed thereinto but may be delivered thereto by means of a hopper, traveling belt, or other automatic means. Therefore the machine must work on the stock when it is lying flat on the table and not on edge as in the usual machines of this character.

The machines now in use have a number 75 of practical defects, when it comes to operating at high speeds, which we have succeeded in eliminating by making certain improvements and changes in the mechanisms and arrangements of the parts of such a 80 machine. These changes are, in part, as follows:—We pass the stock through the machine lying flat instead of on edge. This enables us to have the axes of the cutter heads and of the feed rollers at right-angles 85 to each other, instead of parallel, and we therefore do not have to use toothed drive wheels against the edge of the stock but we use pairs of rollers, in vertical alignment, on 90 each side of the stock, using two such pairs of rollers on the feed side of the machine and one pair on the delivery side thereof. These rollers are smooth faced and engage 95 the finished surfaces of the stiles. This arrangement also insures that the stock shall not be bent or otherwise distorted by the 100 rollers but that their only action on the stock is to apply a straight horizontal force thereon against the backward force of the cutter head knives against which the stock 105 is being fed. And since the rollers extend entirely across the broad surface of the stock, no matter what its width may be, this force is distributed across the whole face of the wood, on both sides, and is not applied to one narrow edge only, as in the

usual construction. This arrangement also permits of a positive delivery of the last piece of stock in a batch thereby preventing its stopping as soon as it has passed the feed rollers and while still in engagement with the cutter head and thus preventing the knives from burning the wood at the point where the stock stopped. This cannot be done, without damaging the finished edge 10 of the stock, on machines which feed by engaging the edge of the stock.

Since the feed rollers and the cutter heads are on axes at right-angles to each other, it is possible and convenient to use direct 15 electric drive for the several parts, one motor being used to feed the stock to the machine and away therefrom, and two other motors, rotating in opposite directions, being used to drive the two cutter heads which 20 are directly connected thereto and which operate on the stock to form the edges thereof as it passes therethrough. Thus it will be seen that the three driven parts are 25 entirely independent of each other though normally the two cutter head motors are wired to be controlled together. This 30 enables us to run the cutter heads at a very high rate, 3,600 revolutions per minute, or more, and to drive the stock through the machine at a much higher rate than has heretofore been possible or practicable, increasing this feed from a rate of sixty to one-hundred-and-fifty feet per minute.

The change in the position of the stock 35 necessitates, of course, that the cutter heads be rotated on vertical axes. The said cutter heads are placed in alignment exactly across the width of the stock, thus working simultaneously on two opposite points thereof 40 and thus preventing any distortion of the cut surface due to any irregularity in the alignment of the edges of the stock; in other words the two edges are cut exactly parallel with each other whether the stock is slightly 45 curved by warping or is straight. This fact enables us to use a large number of otherwise defective pieces because their width is uniform and they can be assembled in doors under pressure, oppositely warped pieces 50 being used on opposite edges of the door and all straightened under pressure and glued thus together to produce a straight door, thus using up waste pieces of stock. This cannot be done when the cutter heads 55 are not in alignment across the stock, as in the ordinary arrangement of such machines, because as the warped piece passes through the machine its amount of offset from the straight line varies as the respective portions reach the two cutter heads and this 60 makes a stile or rail of varying width which cannot be used in a door. This particular feature is further taken care of by the means we use in guiding the stock through

the machine as particularly illustrated in Fig. 5.

Further difference is found in the fact that though one cutter head and the corresponding guide parts are all simultaneously and equally adjustable yet the feed mechanism is fixed in its position, not being adjusted to different widths of stock, thus eliminating one source of trouble in the operation of such a machine.

A further change is found that though 75 one cutter head may be adjusted horizontally equally and simultaneously with the table and guides yet both cutter heads may also be independently and quickly adjusted, both horizontally and vertically, without 80 the operator having to pass around the machine, all said adjustments of each of the cutter heads being made at one place.

Again, a further change is made in the general form of the machine in which the massive base holds all the cutting and guiding parts at or below the working level of the table, thus making these parts free from vibration and also placing them in positions convenient for use, for adjustment, for 90 inspection and repair or replacement, while that part of the machine which is above the level of the working table contains only the feed motor and the apparatus connected with driving and controlling the pressure 95 of the feed rollers.

Another change is found in the mechanism by which the pressure of the feed rollers on the stock is regulated and whereby their motion is limited and controlled; all 100 the movable members of the pairs of feed rollers being equally and simultaneously adjusted as to their pressure and the limits of their action, and may also be independently adjusted as to their pressure on 105 the stock. Therefore, if the thickness of the stock to be fed in the machine changes from time to time, all the feed rollers can be 110 equally adjusted to take care of the change in thickness whereby the actual pressure will be kept the same, if desired, in spite of the change in thickness.

Referring now to the drawings, it will be seen that the base of the machine is provided with a single bed-plate 1 on which two pedestals 2 and 3 are securely fastened. The pedestal 2 is on the feed side of the machine and the pedestal 3 is on the delivery side thereof. The pedestals 2 and 3 are spaced apart to provide room for the two vertical electric cutter head motors 4 and 5. A rear table 6 extends in one structure from end to end of the machine and is secured to both the pedestals 2 and 3 and is formed with an opening 7 through which the rear motor 4, with its arbor and cutter head 8, projects.

A front table 9 also extends from end to

end of the machine in one single structure and is slidably mounted on top of both of the said pedestals 2 and 3 and has its working surface in the same horizontal plane as the working surface of the said rear table 6. The front table 9 is provided with an opening 10 for the front motor 5 and its cutter head 11 and also with arched bridges 12 which span over the portions of the three lower feed rollers which are not in engagement with the stock passing through the machine. The said front table is guided in its motion towards or away from the rear table 6 by suitable means engaging in the parallel slots 13 in the pedestals and may be secured in any adjusted position by means of the hand wheel clamps 14. The slots 13 extend rearward from the front of the machine at right-angles to the direction of the feed of the stock. The table 9 is moved in the slots 13 towards or away from the axis of feed, when the clamps 14 have been loosened, by means of a suitable screw shaft 15 engaging it and the bracket 16 secured to the pedestal 2.

Each of the motors 4 and 5 is mounted on independent carrier plates 17 which are vertically movable between guides 18 forming part of the horizontally movable carriages 19 and 20 which are mounted between horizontal guides 21 formed on the inner vertical surface of the said pedestal 2. The vertical adjustment of each of the two motors 4 and 5 is similar and comprises a nut 22 mounted on the back of the plate 17 and engaging a vertical screw 23 which is mounted in the carriage 19 or 20. The screw 23 is rotated by a pair of spiral gears 24, one of which is secured to the screw 23 and the other of which is slidably mounted on the operating shaft 25 or 26. The shaft 25 operates the gears for the rear carriage 19 and the motor 4 while the shaft 26 performs the same function for the front carriage 20 and its motor 5. These shafts 25 and 26 are mounted in the pedestal 2 and extend suitable distances inward from the front. Each shaft is squared at its end to receive the usual operating wrench handle. Thus by turning the shaft 25 the rear cutter head 8 can be raised or lowered independent of its horizontal adjustment, and by turning the shaft 26 the front cutter head 11 can be similarly adjusted independent of its horizontal position.

The rear carriage 19 may be horizontally adjusted by means of a screw shaft 27, mounted in the pedestal 2 in similar manner as the shafts 25 and 26, and engaging a nut 28 secured to the said carriage 19. Thus the horizontal position of the rear cutter head 8, motor 4, and carrier plate 17 may be adjusted by rotating the shaft 27.

The front carriage 20 may be horizontally moved to adapt it for use with different

widths of stock and to adjust it relatively to the front table, by means of a similar screw shaft 29 engaging a nut 30 on the carriage, thus adjusting the horizontal position of the cutter head 11 independently of its vertical adjustment and also independently of the adjustment of the front table 9, as above described. But, it is usually desired to move both the table 9 and the cutter head 11 equal amounts without disturbing their relative positions. In order to accomplish this we mount a sprocket gear 31 on the above described screw shaft 15, which controls the position of the sliding table 9, and connect it to a similar sprocket wheel 32, loosely mounted on the said screw shaft 29, by means of a sprocket chain 33. The sprocket wheel 32 is provided with clutch teeth on its inner face while complementary teeth are formed on the adjacent face of a clutch disk 34 which is fixedly mounted on the said screw shaft 29. Thus when the sprocket 32 is in engagement with the disk 34 any rotation of the screw shaft 15 will make a corresponding rotation of the screw shaft 29 and if their respective screw pitches and the pitch diameters of the sprocket wheels 31 and 32 are equal, or are inversely proportional, then the horizontal motions of the table 9 and its cutter head 11 will be equal and the adjustments of the said parts will not be in any way altered.

The feed mechanism comprises pairs of wide rollers, one roller of each pair being fixedly mounted in the pedestals 2 or 3, while the other of each pair is mounted on spring depressed carriers which permit the said roller to rise and fall with changes in the thickness of the stock being fed in the machine. As all these pairs are similar one only will be described, it being understood that there are two pairs feeding the stock to the cutter heads and one pair drawing it away therefrom.

The lower feed roller 35 is mounted in bearings 36 in the pedestal. These bearings are preferably provided with an inclined adjustment arranged to approximately correspond with the motion of the center of the upper feed roller 37, of the pair, so that any change in the diameter of the rollers will bring their lines of contact with the stock substantially one above the other. This inclined adjustment of the bearings is also substantially tangential to the line of contact of the gears driving the roller so that any reasonable adjustment of the bearing will not materially affect the gear action or wear. As before stated, the feed roller 35 is broad enough to cover the width of any stock which the machine can take, and the movable table 9 spans over each of the said rollers 35 by means of arched bridges 12.

The upper feed roller 37 is mounted in a swinging frame or cradle 38, pivoted at 39

to the upper extension 40 of the pedestal 2 or 3. This frame 38 and pivot 39 are arranged so that there is but very slight longitudinal motion of the point of contact of 5 the roller 37 with the stock with different thicknesses of the stock being fed.

The frame 38 is pressed downward by means of a spring actuated mechanism mounted on top of the said upward frame 10 extension 40. This mechanism comprises a longitudinally fixed but rotatable shaft 41, extending lengthwise along the machine and mounted in brackets 42 on the frame 40. This shaft 41 has three sets of screw-threads 15 43 cut thereon at suitable positions and each of these screw-threads engages a thread cut in the interior of a surrounding sleeve 44, so that by turning the shaft 41 the said sleeves 44 are moved longitudinally. In the particular machine described, two of these threads are right-handed and one left-handed in order that the motions of all three of the sleeves 44 may make corresponding and equal adjustments because two of the rollers 20 37 are mounted to the right of their pivots 39 while one is mounted to the left thereof. The sleeves 44 do not rotate, being held therefrom by a part of the hereinafter described mechanism. Each sleeve is screw-threaded on its outer surface at one end to receive the hand adjusting wheel 45 which screws thereon and fixes or adjusts the position of the spring cup 46 on the said sleeve 44. The pressure spring 47 is wound around 25 30 the sleeve 44 and is compressed between the said cup 46 and another cup 48 formed on or adjacent to the sliding head 49. A fixed stop 50 is secured to the sleeve 44 on the other side of the head 49 and is shown for 35 clearness as pinned thereto but is preferably screwed thereon and therefore adjustable. The head 49 is preferably square and slides freely on the sleeve 44 but engages it by means of a key and slot (not shown) in the 40 usual way, thereby holding the sleeve from turning. Vertical grooves are provided on the sides of the head 49, near its center, and are engaged by suitable riders mounted on the tines 51 of the forked lever which is 45 pivoted at 52 to the extension 40. A lever 53 is attached to the pivot 52 and extends out therefrom over the frame 38, carrying the roller 37, and is attached thereto by a link 54. Therefore, from the above description 50 it is readily understood that, the pressure of each of these three springs 47 is independently controlled by the adjustment of its hand wheel 45 but that the pressure of all of the rollers 37 may be correspondingly increased or diminished by rotating 55 the shaft 41, thus moving all of the sleeves 44 with their hand wheels 45 equal amounts and therefore changing the pressure of the respective springs. Also the rotation of the 60 shaft 41 moves the stops 50, with the sleeves

44, and therefore adjusts the position of the rollers 37 when there is no stock being fed under them. In practice the pressure of the rollers 37 is adjusted so that the roller next to and feeding towards the cutter heads engages the stock with a considerably greater force than either of the other two rollers. 70

All the rollers 35 and 37 are rotated at exactly the same speed by the following mechanism. A feed motor 55 is mounted on the extension 40 of the pedestal 2, and drives a pinion 56 which engages and drives the large main gear wheel 57 to which the second pinion 58 is attached. This second pinion 58 engages and drives the the second 75 large gear 59 to which the smaller distributing gear wheel 60 is attached. The shaft of these wheels 59 and 60 is concentric with but detached from the pivot pin 39 of the roller carrier frame 38 and therefore all 80 adjustments of the roller 37, due to variations in the thickness of the stock, are made about the central axis of these wheels. The wheel 60 meshes with three other wheels of equal size, the upper two, 61, being mounted on the shafts of the two feed rollers 37, while the third wheel 62 forms the distributing wheel for the lower feed rollers 35, meshing with the two equal gears 63 on the shafts of the said rollers 35. The 85 rollers 35 and 37 to draw the stock away from the cutter heads, after it has passed them, are interconnected by corresponding gears 60, 61, 62 and 63 and they are driven by means of a sprocket chain 64 connecting 90 a sprocket wheel 65, on the shaft of one of the lower rollers 35, with the corresponding sprocket wheel 66 on the shaft of the delivery feed roller 35. 95

Thus it will be seen that the stock fed through the machine and delivered therefrom is driven by rollers which engage its entire width, which turn at exactly the same rates, and which are mounted in pairs, the rollers of which engage the stock in vertical alignment. Also that the pressure of the rollers is regulated individually and collectively and is resilient in its nature. 105

Referring now principally to Fig. 5 wherein the stock guiding means is illustrated. This machine is intended particularly for use on built up stock, that is to say on stock comprising a core with layers of veneer or ply wood on its outer flat faces and therefore, if the ply wood should happen to be poorly glued to the core at any point of its extreme edges, which are cut by the knives of the cutter head, the said knives may tear the veneer and spoil the resulting stile. In order to prevent this action we form the tables 6 and 9 so as to remain in contact with the under side of the stock as it passes the two cutter heads 8 and 11 and we also provide complementary pressure shoes 67 which engage 110 115 120 125 130

the upper side of the stock immediately over the edges of the said tables 6 and 9. Said shoes 67 are mounted on rods 68 (Fig. 2) which are pressed down by springs, not 5 shown, in the vertical cylinders 69, the pressure thereof being regulated by the hand wheels 70. The said cylinders 69 are each supported by one of the hereinafter described lateral guide plates.

10 The lateral guides for the stock comprise a plurality of fixed adjustable guide plates on the rear side of the stock and spring actuated guide wheels on the front side thereof. Each guide plate is provided with 15 slots through which the bolts or studs which secure it to the table 6 or 9 pass and by which it may be adjusted in position. The guide plate 71 is on the delivery side of the rear cutter head 8 and engages the 20 finished edge of the stile or rail. The guide plate 72 is on the feed side of said cutter head 8 and extends a short distance to the right therefrom. The guide plates 73 and 74 extend the guide line on the feed side 25 from the said plate 72. As shown in the drawings the plate 72 has its guide edge parallel with the direction of motion of the stock through the machine but the plate 73, next to it, is turned slightly from said parallel 30 position so that its right hand corner is further from the normal straight feed line, while the third plate 74 is still further turned from said parallel position and its left hand corner is made contiguous with 35 the right hand corner of the second plate 73. Thus the line of said guide plates may be substantially a curved line ending in a line parallel to the direction of feed. This digression from the straight line is exaggerated 40 in the drawings.

The front edge of the stock is guided by a plate 75 on the delivery side of the front cutter head 11 and by two pairs of spring-actuated guides on the feed side thereof, 45 said spring guides being positioned opposite to the above described guide plates 72 and 73. These spring guides each comprise a pair of guide wheels 76 mounted on a yoke 77, which is pivotally mounted on the 50 end of a rod 78. This rod 78 is mounted in a bracket 79 on the table 9 and has a second rod 80 screwed into it and extending therefrom to the front of the table where it is provided with a hand wheel 81. This rod 55 80 has a flange or shoulder 82 which is engaged by the end of the spring 83, which therefore presses the guide wheels 76 towards the stock. The outer end of the 60 spring 83 is engaged by the adjustable screw 84 in the bracket. Thus by turning the hand wheel 81 the distance between the wheels 76 and the shoulder 82 is increased or diminished and therefore the spring 83 is more or less compressed between the 65 shoulder 82 and the screw 84.

In practice the stock is fed with its advancing corner engaging the rear guide plate 74. Since the feed rollers drive the stock in a straight line through the machine, and since the guide plates 73 and 74 are inclined 70 to that line, it is evident that the stock is pressed firmly against said guides by the action of the feed rollers. The adjustment of the pressure spring 47 of the first pair of feed rollers is made much lighter than that 75 of the second pair. There is, of course, a very slight sliding action between the stock and the rollers and this action insures that the stock will follow and press against the guide plates as it passes through the machine. If, therefore, a piece of stock which is slightly warped on one edge is inserted in the machine with the concave edge towards the rear guides 72, 73 and 74 it follows the 80 curved line of the guides with the result that its edges are still somewhat curved when it is finished and, since the cutter heads are in alignment, it is of exactly the same width throughout its length as it would have been if it had been straight. This would not have 85 been the case if the guide plates had been in straight alignment and one cutter head in advance of the other, as in the usual construction of such machines, because one of the cutter heads would have taken a larger bite off its ends than at the center and the other would have taken more off the center than at the ends with the result that the moulded edges would have been defective and also the width of the stile or rail would 90 not have been uniform from end to end.

Thus it will be seen that this machine provides a means of working at a much higher rate than any other machine at present made and that bent stock can be used as effectively 95 as straight stock. In practice, however, it is usual to run straight stock at one time and bent stock at another time, the guide plates being slightly adjusted for the condition of the stock. Further, it will be noted that 100 all the cutting and guiding mechanism is mounted in the base of the machine and that the feed mechanism alone is mounted above the working table. Also that the tables are at a fixed height and no change in height of 105 any working part is caused by a change in the width of the stock being used. There is, of course additional apparatus used on the machine but not illustrated in the drawings 110 as it does not relate to the essential invented matter described above.

Having described our invention, what we claim and desire to secure by Letters Patent is:—

1. A sticker for door stiles or rails comprising a pair of fixed pedestals; a fixed rear horizontal table mounted on both said pedestals; a movable front horizontal table mounted on both said pedestals and in the same horizontal plane as the fixed table, said front 125

and rear tables being adapted to support the stock to be worked in flat position near its edges in a continuous structure from end to end of the machine; pressure shoes resiliently mounted on the tables and engaging the upper face of the stock adjacent the cutter heads; a pair of independently rotated and adjusted cutter heads, rotating on vertical axes in transverse alignment relatively to the longitudinal axis of the machine; feed means independently rotated on horizontal axes and engaging the upper and lower flat horizontal faces of the stock to pass it through the machine; fixed guide means mounted on the fixed rear table; and resilient guide means mounted on the movable front table whereby the stock is guided between the cutter heads as it is driven thereagainst by the feed means.

20 2. A sticker for door stiles as set forth in claim 1, wherein said two cutter heads are mounted on independent motors and both motors are mounted in the inner face of one of the pedestals, whereby vibration of the machine is reduced or eliminated.

25 3. A sticker for door stiles as set forth in claim 1, wherein said cutter heads are mounted on independent motors and both motors are independently adjustable; together with

means for moving the movable table; independent means for moving the motor and cutter head corresponding with said movable table; and releasable means interconnecting the moving means of the table with that of the motor, whereby when said interconnecting means is in action and said table moving means is actuated the motor moving means is equally, simultaneously, and correspondingly actuated.

4. A sticker for door stiles as set forth in claim 1, wherein said feeding means comprises three pairs of wide rollers, one of each pair fixedly mounted in the pedestal to engage the under face of the stock in the plane of the tables and the other of each pair resiliently mounted in vertical alignment therewith and engaging the upper face of the stock; two of said pairs located on one side of and feeding towards the cutter heads and the third pair located on the other side of and drawing away from the cutter heads; together with an independent driving motor and interconnecting gears whereby all of said rollers are driven at equal peripheral speeds.

WILLIAM C. HOBART.
FREDERICK A. NICHOLSON.
